UNITED STATES PATENT OFFICE

CHARLES K. WOODBRIDGE, OF FLUSHING, NEW YORK, ASSIGNOR TO DICTAPHONE CORPORATION, OF BRIDGEPORT, CONNECTICUT, A CORPORATION OF NEW YORK

TIMING

Application filed August 21, 1923. Serial No. 658,597.

This invention relates to improvements in methods and apparatus for producing a series of timed, audible or visible signals, as for purposes of rhythm.

One object of this invention is to utilize a sound-reproducing machine for this purpose.

Another object is to produce a regular succession of audible or visible sounds for marking time.

Another object is to utilize a commercial phonograph, to produce audible or other signals, to aid in teaching the art of typewriting by inculcating students with the rhythm of finger action, which is conducive to speed and uniformity of touch.

Another object is to provide a convenient means or method for varying the timing of such signals.

Another object is to provide a simple, inexpensive and fool-proof device for attachment to a phonograph, permitting the available governed movement of the rotating part to cause or directly produce such signals as an incident to its rotation.

Other objects and advantages will herein-after appear.

In the accompanying drawings—

Figure 1 is a plan view of a dictation machine (here shown as a transcribing machine) partially broken away, and showing an embodiment of the present invention attached thereto.

Fig. 2 is an end view of the invention in operative position on the dictation machine as in Fig. 1.

Fig. 3 is an incomplete view of one member of the device attached to part of the machine, showing the manner of adjusting the same to increase or diminish the strength of the sound.

Fig. 4 is a perspective view of an arm adapted to be attached to the reproducer (or recorder-reproducer) of the machine.

Fig. 5 is a perspective view of the mandrel supported member or ring which cooperates

with the arm shown in Fig. 4, and is adapted to be attached to the rotating part of the machine.

Fig. 6 is an end view, partially in cross section, of the dictation machine, showing a modified form of the invention.

Fig. 7 is a perspective view of one of the members employed in this modified form.

Fig. 8 is a fragmentary vertical sectional view, enlarged, of one of the members of this modified form, arranged to vary the volume of sound.

Fig. 9 is a fragmentary end view of the dictation machine, showing a further modified form of the invention attached thereto.

Fig. 10 is a plan view of a reproducer head, showing this modification applied thereto.

Fig. 11 is a front view of the reproducer-head and showing the manner of adjusting the device to vary the volume of sound.

Fig. 12 is a perspective view of the adjustable element of the form shown in Figs. 9, 10 and 11.

Fig. 13 is a diagrammatic view of an arrangement for producing signals at a distance, and showing the idea of a plurality of simultaneously produced signals, and also of signals of different kinds—in this case, both visible and audible ones, although, of course, either type might be used alone.

Similar reference numerals indicate corresponding parts throughout the several figures of the drawings.

One embodiment of the invention shown in the drawings includes a striker-ring 10 (Fig. 5) in the form of a split tube, preferably formed of resilient sheet-metal. The tube has a slight taper, substantially corresponding to that of the mandrel 11 of a dictation or like machine, so as to frictionally hold itself to the mandrel, as shown in Fig. 1, to rotate therewith. This action of the ring 10, which is really a clinging action, is advantageous, since looseness between the ring and the mandrel—due to improper fitting of the

ring—would cause the volume of the tick to be reduced, or would produce a variable and uncertain ticking which, of course, is undesirable and might even render the device largely useless. All this is avoided by having the ring held to the mandrel by its own spring action. Further, the ring 10 is easily applied to the mandrel and may be slipped off instantly, without employing tools, when the phonograph is wanted for other use.

The sliding movement of the ring 10 on the mandrel is limited, and the operating position thus determined by an inwardly-bent stop 13 (Figs. 1 and 5) provided on the ring 15 along one of its edges, which engages the end of the mandrel. This also prevents the ring from being applied with the wrong end toward the mandrel.

The ring 10 has, projecting beyond the end 20 of the mandrel, a yielding striker-tongue 14, bent outwardly and formed by a circumferential slit 14^a (Fig. 5). The tip of the tongue is slightly bent to provide a nib 15 adapted to strike and brush by a relatively-fixed part, such as a sound-box or other sound-producing and transmitting means, hereinafter described, to make a succession of audible sounds as the mandrel is rotated.

The sound-producing and transmitting means may be of various forms, several of which are disclosed herein. In the forms shown in Figs. 1 to 5, and 9 to 12, it is mounted directly upon the usual sound-box carriage 16 (Fig. 1), which is placed at the end of the mandrel 11, where it is free from the feed-screw 17 when the device of the present invention is to be used.

The sound-producer and transmitter, in the form shown in Figs. 1 to 5, includes a yoke 18 secured upon the sound-box carriage 16, by the screws 19 and 20 found on the phonograph, and which project over the inner periphery of the carriage 16 and retain the usual sound-box 21 therein. Between its ends, the yoke 18 carries a finger 24, integral therewith, and bent downwardly from the yoke at right angles thereto, in which position an end 26 of the finger extends into the path of the striker-tongue 14 on the ring 10.

Thus, when the machine is operated, the rotation of the ring 10 (in the direction of the arrow, Fig. 2), together with its striker-tongue 14, causes the nib 15 thereon to strike against the finger 24. This produces a sound which is transmitted through the sound-box carriage, then collected by the diaphragm thereof, and finally, audibly transmitted through a listening-tube 18^a to the person using the device of the present invention. The sound that is heard is sharp and of short duration, and is more accurately defined as a tick, closely resembling the sound produced by a metronome. This is because the end 26 of the finger 24 and the nib 15 on the ring 10 rapidly engage and disengage. As

soon as the connection between the nib 15 and the end 26 is broken, no further audible sound is transmitted, even though the tongue 14 may continue to vibrate; and the finger 24 is prevented from audibly vibrating by forming it with a stiffening rib.

In order to vary the volume of the ticking sound, the finger 24, with its yoke 18, may be adjusted to and from the path of the tongue 14. This is done by loosening the screws 19 and 20 (Fig. 3) and moving the yoke upon the sound-box carriage, the yoke being provided with notches 22, 23. The yoke may move bodily, or it may be swung about one of the screws 19—20, as shown in Fig. 3, to alter the position of the finger 24. This last is the preferred method, since one of the screws may be fairly tight and the machine allowed to operate until the repeated contact of the tongue 14 with the arm 24 jogs it to the position where the sound best suits the person using the machine.

The frequency or timing of the ticks or sound may be regulated to suit the desired conditions by means of the usual, manually-operable speed adjustment 12 (Fig. 1) of the speed governor, which may be of any suitable type, for instance that shown in the patent to Woods #1,186,638, or such as is now found in commercial talking machines. The speed adjustment may be such as to cause the signals to be given at uniform intervals, or it may be arranged to gradually accelerate or retard the frequency of the signals in accordance with the will of the operator or a predetermined plan. To accomplish the latter automatically, it is merely necessary to provide a feed-screw or other device for causing the speed adjustment 12 to be moved continuously or intermittently at predetermined times during the operation of the signal device.

The yoke 18, at its portion adjacent the finger 24, is held to the sound-box carriage by a bent-over portion 25 close to the under surface of the carriage. This bent-over portion 25, with the body portion of the yoke, thus embraces the carriage and limits any possible movement of the finger longitudinally.

In Figs. 6 and 7, there is illustrated a modified form of sound-producer. This is in the form of an auxiliary sound-box, adapted to be substituted for the usual recorder or reproducer head—the head first being removed from the frame in which it is supported upon an annular flange 27, by removing the holding screws. This auxiliary sound-box consists of a casing including an upper disc-shaped head 28, having a centrally-flanged, tubular outlet 29 to which the listening-tube 30 may be attached. A cone-shaped base 31 is secured to the head and is provided with a peripheral flange 32, engaging the inner cylindrical wall of the frame and resting upon the flange 27. A hardened steel point 33 is

provided centrally of the conical section and projects into the path of the spring leaf 14 of the ring 10 (Fig. 6), and which engages it periodically as the ring is rotated. With this form of the invention, the periodic ticking sound produced upon the hardened steel point is amplified directly within the sound-box and transmitted through the listening tubes to the operator.

10 In Fig. 8, there is illustrated a modification of the form of sound-producer shown in Figs. 6 and 7, adapted to permit of the adjustment of the point, to increase or diminish the ticking volume. In this form, the conical end of the head is provided interiorly with screw-threads 34, and the hardened steel point 35 is screw-threaded to engage the same, being rounded at its exposed end to engage the spring leaf of the ring, and being provided at its inner end with a kerf 36 adapted to be engaged by a screw-driver, or the like, inserted through the tubular outlet of the head, to adjust the degree of projection of the point, and thereby the ticking volume.

25 In Figs. 9 to 12, there is illustrated a further modified form of the invention. The sound-producer consists of a finger 37, arcuate in shape and adapted to overlie the forward inside quarter of the reproducer head-frame, and being provided at its inner end with a downwardly-bent finger 38, disposed at the side of the reproducer-head and tapered to a point, extending into the path of the spring-leaf 39 of a ring 40 (Fig. 9). This ring is slightly different than the ring 10 provided in the other forms shown in Figs. 1 to 8; for, the spring-tongue or leaf 39 is provided at the inner end and the stop-lug 41 at the outer end, while the ring 10 has the tongue 14 at its outer end and the lug 13 near its inner end.

30 A pair of holes 42 and 43 (Fig. 12) are provided adjacent the forward end of the member 16, at either side of an angular bend 44, the extremity of the member being secured by a screw 45 extending through the hole 42. A set screw 46 engages the hole 43, preventing angular movement of the member about the screw 45, and putting the member under tension, so that by adjusting the screw 46, the degree of engagement of the finger 38 with the spring-leaf 39 may be regulated, and thereby the ticking volume increased or diminished, as desired. The normal function of the screws 45 and 46 is to attach the pointer or index 47 of the reproducer-head.

35 The invention disclosed herein provides an audible timing device of extreme simplicity, and one which operates with the greatest precision. It is, furthermore, capable of very close adjustments, either as to timing or volume. The same may be readily attached to, or removed from, dictation machines, without the necessity of making any changes therein to accommodate it; and it cannot, in

any way, injure the delicate sound-reproducing mechanism of the machine, either through its ordinary operation, or from careless or improper usage.

40 As shown in Fig. 13, the present invention also includes the provision of a regular succession of visible, as well as audible, signals and also the combination of the two. These may be controlled at a distance by the attachment to the phonograph, by arranging the ring so that it will close an electric circuit 50 when it engages the box 31. The circuit 50 has a source of current supply 51, a lamp 52, and a solenoid 53 all arranged in series. The solenoid operates a striker 54 for a bell 55 against the tension of a spring 56 when the circuit is closed to produce the audible signal. At the same time, the lamp 52 glows and gives the visible signal. The circuit is maintained closed for a short interval, because of the shape and position of the parts, so that the lamp may have time to come to substantially full brilliancy for each signal.

45 The timbre of the audible signal may be varied as desired by making the various parts of suitable material.

50 It should be understood that the present invention may be applied to other forms and types of talking machines and other sound-producing or other movement-imparting machines, and that portions of the invention may be used without others. For instance, the ring 10 may be provided as an attachment 55 separate from the means which it engages to produce the sound, and it may be made of any shape to produce the results herein-described.

55 Moreover, attention is invited to the fact that applicant's conception is not limited to the specific embodiment herein disclosed, but may, in fact, have a very wide and ever-growing field of use. For instance, in the field of safety engineering, it is highly desirable to provide an automatic signal, operating with the movement of a machine which will give a warning when the operation has progressed to a predetermined part of its cycle. This signal might be a visible one—such as the movement of a small, mechanically-operated warning or danger flag, to a position in front of the operator's fingers to warn him, for instance, that the machine is about to close; it might include a double signal, such as a tick or a bell; or it might include a combination of two or more dissimilar signals. A visible signal depending upon the faculty of sight, in combination with another signal depending upon the faculty of hearing, would presumably furnish an added safeguard over either type of signal used alone. The inventor's concept is broadly,—first, to a signal, automatically operated as an incident to the operation of a machine, 100 or other movement-imparting device; and

105 110 115 120 125 130

second, to a combination of a plurality of different kinds of signals operated automatically in this manner.

Further, the device of this invention may be used as an adjunct or auxiliary to machines to be operated manually at predetermined times. In this case, the signals would serve as a guide to the operator to indicate the times when the machine should be operated, and will tend to keep the operator working at the required speed.

Variations and modifications may be resorted to within the scope of this invention, and portions of the improvements may be used without others.

Having described the invention, what is claimed is:

1. In combination, a rotating record-support having a contact member, a second contact member disposed in the path of the first contact member, one of the members being resilient, and means whereby the members produce staccato sounds upon contact with each other.
2. In combination, a rotating record-support having a contact member, a second contact member disposed in the path of the first contact member, means whereby the second contact member may be moved to a greater or less degree into the path of the first contact member, and means for fixing the second member in such adjusted position.
3. In combination, a rotating record-supporting mandrel, and means adapted to be removably mounted upon the mandrel interchangeably with a record to produce periodic timing-signals.
4. In combination, a rotating mandrel, a spring sleeve mounted upon the mandrel, striker-means carried by the sleeve, and means adapted to be intermittently struck by the striker-means to produce audible timing-signals.
5. In combination, a rotating mandrel, a split resilient sleeve slidably mounted upon the mandrel, an integral arm bent therefrom and adapted to abut with the end of the mandrel to limit the sliding movement of the sleeve on the mandrel, a projecting spring leaf bent from the sleeve, and means adapted to be intermittently engaged by the spring-leaf to produce periodic timing-signals.
6. In combination, a rotating member, a soundbox, a sound-box having a diaphragm support, means for retaining the sound-box in the support, and a member unconnected with said diaphragm and secured in vibration-transmitting relation to the sound-box by the sound-box retaining means, the member being adapted to be intermittently engaged by the rotating member to produce periodic audible timing-signals.
7. In combination, a rotating member, a sound-box having a vibration responsive member, a contact member having means dis-

posed in the path of said rotating member to be intermittently engaged thereby to produce audible timing-signals, means for mounting said contact member in spaced relation to said vibration responsive member, said last means being adapted to permit adjustment of said contact member to regulate its engagement with the rotating member and to prevent accidental displacement thereof.

8. In combination, a rotating record-support, a sound-box for reproducing sound recorded on a record adapted to be mounted on the record-support, and a timing-mechanism including means on the record-support and means on the sound-box adapted to contact and produce an audible signal.

9. In combination, a rotating record-support, a sound-box for reproducing sound recorded on a record adapted to be mounted on the record-support, timing-mechanism including means on the record-support and means on the sound-box adapted to intermittently contact and produce audible signals, and a speed regulator for controlling the rotation of the record-support to vary the time interval between signals.

10. In combination, a rotating record-support, a stationary member, and a timing-mechanism including a member mounted on the stationary member and another member removably mounted on the rotating record-support adapted to contact with the member on the stationary member to make an audible sound as the record-support rotates.

11. As a new article of manufacture, a device for attachment to a rotating record-support of a phonograph to intermittently produce ticking sounds as an incident to its rotation.

12. As a new article of manufacture, a device for attachment to a rotating record-support of a phonograph, including a striker adapted to produce a sound when the record-support rotates.

13. As a new article of manufacture, an attachment for phonographs adapted to be attached to the rotating member thereof having means for causing short, sharp individually audible sounds to be produced in succession at regular intervals as an incident to the rotation thereof.

14. As a new article of manufacture, an attachment for phonographs having a rotating member, said attachment being adapted to frictionally and detachably engage the rotating member therefor and having means for causing signals to be produced as an incident to the rotation of the rotating member.

15. In combination, a continuously driven record-support, and means comprising a member co-operating therewith to simultaneously produce periodic audible and visible timing-signals as a result of such co-operation.

16. In combination, a continuously driven

record-support, and means comprising a member co-operating therewith to produce at a distance, periodic separately perceptible timing-signals as a result of such co-operation.

CERTIFICATE OF CORRECTION.

Patent No. 1,781,041.

Granted November 11, 1930, to

CHARLES K. WOODBRIDGE.

It is hereby certified that error appears in the printed specification of the above numbered patent requiring correction as follows: Page 4, line 54, claim 6, strike out the words "soundbox, a sound-box having a diaphragm" and insert instead "sound-box having a diaphragm a sound-box"; and that the said Letters Patent should be read with this correction therein that the same may conform to the record of the case in the Patent Office.

Signed and sealed this 6th day of January, A. D. 1931.

(Seal)

**M. J. Moore,
Acting Commissioner of Patents.**
